Primary Examiner — Christian P. McLean*Assistant Examiner* — Laura H Yu(74) *Attorney, Agent, or Firm* — Kunzler Bean & Adamson, PC; Bryan Pitt(57) **CLAIM**

The ornamental design for a tape with protective case, as shown and described.

DESCRIPTION

FIG. 1 is a top, front, right side perspective view of a tape with protective case showing my new design;

FIG. 2 is a bottom, front, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded view thereof.

The broken lines show the features of the tape with protective case that form no part of the claimed design.

1 Claim, 9 Drawing Sheets(56)
